UNITED STATES PATENT OFFICE.

REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE.

INTERNAL-COMBUSTION ENGINE.

Application filed January 28, 1924. Serial No. 688,951.

To all whom it may concern:

Be it known that I, REINHARD HILDEBRAND, a citizen of Germany, a resident of Webster Groves, in the county of St. Louis, State of Missouri, have invented certain new and useful Improvements in Internal-Combustion Engines, of which the following is a full, clear, and exact description, reference being had to the accompanying drawing, forming a part of this specification.

This invention relates to improvements in internal combustion engines, and the novel features are particularly adapted for use in oil engines wherein the fuel is discharged into air at a temperature high enough to ignite the mixture.

The main object of the invention is to obtain a thorough mixture of the air and liquid fuel. More specifically stated, an object is to obtain a very effective mixture by using nozzles whereby liquid fuel alone is injected into the hot air, thus dispensing with the compressed air ordinarily used for the injection of the fuel.

Prior to this invention, engines of this type have been provided with nozzles for the injection of the liquid fuel alone, but this is regarded as a rather modern departure involving problems that are not generally recognized, and great difficulty has been experienced in obtaining even a fair degree of efficiency from such nozzles. The problem lies in the mixing of a body of liquid fuel with the highly heated air, the object being to ignite and completely consume the fuel during a very brief period. Heretofore two or more streams of liquid fuel have been discharged from opposing nozzles pointing toward the middle of the combustion chamber, and the theory has been that the combustion will be completed when the liquid reaches a point midway between the nozzles. However, I have found that the fuel in the opposing streams is not completely burned when the midway point is reached, and that some of the fuel particles of the two streams pass beyond this point. This is not desirable because it overcharges the central part of the combustion chamber with fuel oil, and the fuel passing the midway point comes into contact with burned gases, instead of air, and this results in incomplete combustion.

My object is to distribute fine particles of

liquid fuel through the hot air in the combustion chamber by means of two or more streams of fuel so arranged that they penetrate almost all of the space in the combustion chamber, without penetrating each other. This combination and arrangement of elements results in a substantially uniform combustible mixture which is readily ignited and consumed, thereby obtaining high efficiency and all of the other advantages resulting from approximately complete combustion. Instead of attempting to discharge the liquid fuel to a point of impact, or otherwise causing one stream of liquid to retard or interfere with another, I preferably discharge the fuel in the form of fine sprays which freely enter into and commingle with the air throughout the combustion chamber.

In the preferred form of the invention, fuel-injecting nozzles are arranged to discharge conical sprays of finely divided fuel from opposite sides of the combustion chamber. These sprays of liquid move in opposite directions, but the nozzles are offset relative to each other, so the fine particles of liquid in each spray will freely penetrate the air in the combustion chamber, without impinging against or uniting with another spray. The offset nozzles discharge their conical sprays through different portions of the combustion chamber, and said nozzles are preferably so arranged that the sprays will lie alongside of each other with the apex of one conical spray adjacent to the base of another correspondingly formed spray. The fine sprays can thus be produced in the form of reversely arranged cones extending from side to side of the combustion chamber, and by making the walls of the combustion chamber conform approximately to the shape and dimensions of the sprays, I obtain a substantially uniform combustible mixture throughout the combustion chamber.

It is apparent that the highest efficiency is obtained in the use of an internal combustion engine of the type disclosed herein only when the liquid fuel and the air within the combustion chamber are thoroughly mixed, and therefore my improved engine has been provided with means for creating turbulence within the combustion chamber whereby said elements are completely commingled, thus

producing within said combustion chamber a combustible mixture which will be quickly and completely consumed.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

15 Fig. I is a horizontal section through the combustion chamber forming a part of my improved internal combustion engine.

Fig. II is a fragmentary vertical section showing portions of a piston, cylinder and cylinder head provided with a charge-mixing device made in accordance with my invention, said view also showing the means for creating turbulence within said combustion chamber.

25 1 designates an engine cylinder provided with a piston 2, and 3 designates the cylinder head containing valves 4 and 5 to control the admission of air and the discharge of products of combustion.

30 The combustion chamber is formed in the cylinder head 3, said combustion chamber comprising a cavity 7 of a shape illustrated clearly in the drawing.

Fuel-injecting nozzles 9 extend through 35 opposite sides of the cylinder head, and it will be important to observe that these nozzles are not in alinement with each other. They are offset to discharge the liquid fuel across different portions of the combustion 40 chamber. Each nozzle is adapted to discharge a conical spray of fuel, and owing to the arrangement of the nozzles, the sprays are in the form of a double cone with the conical elements alongside of each other. 45 The apex of each conical element lies adjacent to and at one side of the other conical element, and the adjacent sides of the sprays are approximately parallel with each other.

The conical sprays preferably extend 50 across the end of the piston, and the combustion chamber conforms approximately to the shape and dimensions of the sprays. If the combustion chamber contains inlet and exhaust valves 4 and 5, it will not be convenient or desirable to make its walls conform precisely to the shape of the conical sprays. However, this general shape can be rather closely adhered to, as shown by the drawing. The nozzles 9, as will be noted by referring 55 to Fig. II, are inclined toward the piston. The cavity 7 in the cylinder head contains the valves 4 and 5, but Fig. II shows that its upper face lies approximately parallel with the top line of the sprays, and Fig. I shows that it has side walls conforming approxi-

mately to the angle of the outer sides of the sprays.

While my combustion chamber is a single cavity, a careful examination of the drawing will show that in effect it is composed of a pair of conical cavities in free communication with each other and that each of said conical cavities conforms approximately to the shape of the spray which issues from the nozzle at the small end of said conical cavity. The cavities should be so long that the sprays will not be forcibly discharged onto the walls at their relatively wide ends.

To appreciate the results of the combination herein disclosed, one should observe that if each minute particle of liquid fuel in a fine mist, or spray, is entirely surrounded by the air, a highly combustible mixture will be obtained. It is especially desirable to produce this condition through the entire body of air in the combustion chamber. On the other hand, if the sprays were discharged into each other, there would be a tendency for the liquid particles to unite and form relatively large drops, which would not be consumed, and if the sprays were forcibly discharged onto the walls of the combustion chamber, the liquid on the walls would likewise tend to unite and it would not be completely surrounded by the air. Furthermore, if the sprays were discharged into each other, the liquid particles of one spray would enter the combustion space of the other spray and come into contact with burned gases instead of air.

The offset nozzles produce separate and distinct sprays wherein the tiny liquid particles diverge from each other, and there is no opportunity for the sprays to unite and form relatively large drops. Furthermore, the combustion chamber conforms approximately to the shape and dimensions of the sprays, thus avoiding the consequences of discharging the liquid fuel onto the walls of the combustion chamber. Almost all of the air in the combustion chamber is penetrated by the sprays, and each minute particle of liquid fuel is surrounded by the hot air.

It is extremely important, in the operation of internal combustion engines of the type disclosed herein, that the liquid fuel and the air within the combustion chamber be thoroughly mixed and therefore I provide means for compelling the complete commingling of these elements which means will now be described.

Formed in the lower wall of the combustion chamber is an opening 8. The opening 8, as will be seen by referring to Fig. II of the drawing, is of much smaller diameter than the diameter of the cylinder of the engine, said opening being preferably elliptical in shape, and is so arranged that its longest dimension extends diagonally across the lower portion of the combustion

chamber. It is also clearly shown in the view mentioned that the lowermost portion 10 of the wall in which said opening 8 is formed is inclined upwardly toward said opening. It will be understood that this upwardly inclined portion 10 of the lower wall of the combustion chamber is annular in plan, said inclined portion of said wall completely surrounding the opening 8. Arranged at the upper end of the piston 2 is a conical portion 2'. The annular inclined face of the conical portion 2' of the piston is arranged at the same inclination as the annular portion 10 of the lower wall of the combustion chamber.

In the operation of an engine made in accordance with my invention the upwardly moving piston will cause the air within the engine cylinder to be forced through the opening 8, the inclination of the portion 10 of the lower wall of the combustion chamber and the inclinations of the conical portions 2' of the piston 2 coacting in such manner as to direct all of said air toward said opening. The opening 8 is of much smaller diameter than the diameter of the engine cylinder, hence this air will be forced through the opening 8 with great velocity whereby considerable turbulence will be caused within the combustion chamber. This turbulence will cause the thorough commingling of the air and liquid fuel within the combustion chamber whereby a quick and complete combination will result. While I have illustrated a four-cycle engine in the drawing, it is to be understood that my invention is not limited to four-cycle engines but that by changing the structure slightly my invention might be incorporated into a two-cycle engine. Neither do I limit myself to two sprays, but for larger engines might use three or more.

I claim:

1. An internal combustion engine having a cylinder, a piston within said cylinder, a combustion chamber, and fuel-injecting nozzles arranged to discharge conical sprays of fuel at opposite sides of said combustion chamber, said nozzles being arranged at opposite sides of the combustion chamber and offset relative to each other so that the conical sprays will not impinge against each other, said combustion chamber having walls conforming approximately to the shape and dimensions of said conical sprays, and a wall of said combustion chamber being provided with an opening of smaller diameter than the diameter of the cylinder through which opening air is forced by said piston to create turbulence within said combustion chamber.

2. An internal combustion engine having a cylinder, a piston within said cylinder, a combustion chamber, and fuel-injecting nozzles arranged to discharge conical sprays of fuel at opposite sides of said combustion chamber, said nozzles being offset relative to each other so that the sprays will not impinge against each other, said combustion chamber having walls with inclined faces conforming approximately to the shape of said conical sprays, one of said walls being located adjacent to said cylinder and being provided with an elongated opening of smaller diameter than the diameter of said cylinder through which opening air is forced by the piston to create turbulence within said combustion chamber, and said elongated opening being formed diagonally of the combustion chamber.

In testimony that I claim the foregoing I hereunto affix my signature.

REINHARD HILDEBRAND.
